[57] CLAIM

The ornamental design for a combined flower pot, internal support and tubes therefor, as shown.

DESCRIPTION

FIG. 1 is a side elevational view of the combined flower pot, internal support and tubes therefor of my new design;

FIG. 2 is a top plan view thereof;

FIG. 3 is a bottom plan view thereof;

FIG. 4 is a sectional view taken in the direction of the arrows on line 4—4 of FIG. 2; and

FIG. 5 is a bottom plan view of the support portion of my design.
